MORTAR MOUNT

Cecil P. Caulkins, New London, Conn., assignor to
 American Ordnance Corporation, New London,
 Conn., a corporation of Delaware

Application February 14, 1945, Serial No. 577,823

9 Claims. (Cl. 89—37)

1

This invention relates to a mount for a mortar.

Mounts for mortars are usually so heavy and cumbersome that they can be moved only with great difficulty and then only by a considerable number of men. Furthermore, the various sections of a mount are frequently of such a size and weight that they require vehicles for their transportation and are assembled and disassembled only by the expenditure of excessive time and labor. Adjustments for azimuth have presented difficulties and frequently a high degree of precision in adjustment has been almost impossible to attain. Means for elevating and lowering the barrel of the mortar have left much to be desired from the point of ease and speed in attaining the desired setting.

It is therefore, the purpose of this invention to provide a mortar mount that can be readily handled in the assembled condition, by a limited number of men, that can be easily and quickly disassembled into pack-units of reasonable size and weight for personnel transportation, and be easily and quickly reassembled and accurately set and adjusted for both azimuth and elevation.

The specific nature of the invention, as well as other objects and advantages thereof, will clearly appear from a description of a preferred embodiment as shown in the accompanying drawings in which:

Fig. 1 is a perspective view of the complete mortar mount assembly including a supporting leg shown in detached relationship.

Fig. 2 is a vertical section through the base and the middle portion of the carriage.

Fig. 3 is a top view of the complete assembly.

Fig. 4 is a section taken along the line 4—4 of Fig. 5 through the elevating screw.

Fig. 5 is a conventional perspective of the elevating mechanism.

Fig. 6 is a section through a fixed guide showing its relation to the base, to the bearing strip and the auxiliary base support.

Fig. 7 is a vertical section through the locking guide.

Fig. 8 is a perspective view of the traversing screw, pivot stud and traversing screw sleeve, and sliding yoke of the azimuth adjusting assembly.

In Fig. 1 is shown a dish-shaped base 10, having an annular flange 11 provided along its edge with scallops 12 for the purpose of biting into the ground. At the center of base 10 is provided a bearing cup 13 of spherical curvature which

2

supports carriage 20. Radial reinforcing ribs 14 may be provided on the underside of base 10, and said ribs 14 may be further strengthened by a circular plate 15.

5 A plurality of equally spaced handles 16 are preferably secured to the outside of flange 11 for facilitating the handling of the assembled mount. A plurality of equally spaced vertically upstanding channel members 17 are also secured 10 to the outside of said flange, each channel being provided with two pairs of horizontal, axially aligned holes 18 and 19, respectively upper and lower, and braces 17a.

The carriage 20 comprises a circular plate 21 provided at its center with a bearing cup 22 of spherical configuration which engages bearing cup 13 in base 10. The periphery of plate 21 is provided with a somewhat thicker ring portion 23 concentric with plate 21, such ring portion serving the several purposes of providing a reinforcement for plate 21, an annular bearing flange or strip 27 and a base for mounting a graduated azimuth scale 24 by means of screws 25.

25 Since the ring 23 is integral with plate 21 it provides substantial reinforcement to said plate. Furthermore, there are preferably a plurality of radial ribs 26 on the underside of plate 21, joined to both ring 23 and plate 21, so as to provide additional strength. The outer portion of ring 23 is trued on its periphery and upper surface to serve as a bearing strip 27, for a purpose to appear later.

On the upper surface of plate 21 and inside ring 23, there are provided reinforcing ribs 28 merging with an elevating unit housing 29. Two axially horizontal aligned cylindrical bearings 30 are provided in opposite sides of said housing and above them are two arcuate slots 31 concentric with bearings 30, the purpose of which will appear later. Around bearing cup 22 in the center of carriage 20 is provided an integral upstanding bearing cup guide 32 which merges with reinforcing ribs 28, as shown in Fig. 3.

45 The elevating unit 40, as shown in Figs. 3 and 5, consists of a tubular member 41 to which are rigidly attached an elevating handle 42 and a pair of spaced bracket arms 43. Handle 42 projects upwardly and rearwardly, as shown in Fig. 1 in the form of an open end tube to receive a counterweight (not shown) for balancing the weight of the mortar tube 1 and elevating mechanism, to facilitate manual setting. A transverse sleeve 44 with slots 44a is provided in handle 42 with a pin 45, pivotally secured therein and

provided with a threaded hole 45a aligning with slots 44a.

Arms 43 are provided at their extremities with pins 46, said pins being parallel to each other and to the axis of the mortar 100 when in assembled position.

On the pins 46, a supporting unit for the mortar barrel is mounted. Such supporting unit comprises a sliding yoke 47, a connecting yoke 54 and a clamp collar 59-60. Sliding yoke 47 has two parallel integral sliding bearings or sleeves 48 constructed to slidably engage pins 46, whereby yoke 47 may slide on pins 46. A hole 49 is provided through the neck of yoke 47 perpendicular to the plane defined by the axes of sleeves 48. A T-shaped member consisting of a stud 50, provided with an offset transverse sleeve 51, is pivotally secured in hole 49. A traversing screw 55 threadably engages sleeve 51.

The connecting yoke 54 has spaced sliding bearings or sleeves 51a thru which traversing screw 55 is assembled, said screw 55 being thereby rotatably mounted between the arms of yoke 54. A knob 56 is preferably provided on one end of screw 55 for turning same. Sliding yoke 47 may thus be transversely moved relative to connecting yoke 54 and also swivel with respect thereto.

Equally spaced on each side of the center of yoke 54 are two sleeves 57 axially perpendicular to a plane through the arms of said yoke and the axis of traversing screw 55. Pins 58 project rearwardly out of sleeves 57. A split collar 59-60 is provided to clamp around the barrel of a mortar 100, the two segments 59 and 60 being pivotally jointed by means of a pin 61 secured by means of a screw clamp 62. Two sleeves 63 are provided, integrally formed on the lower segment 60, the axes of said sleeves and collar 59-60 being parallel. Sleeves 63 are slidably engaged on pins 58 and thus the barrel of the mortar 100 is supported on elevating unit 40.

In order to secure the mortar 100 in any desired elevation, there is provided a positioning device comprising two tubular members 64 and 65 secured together in axial parallelism (Fig. 5). Tubular member 65 is the longer of the two, projecting beyond both ends of member 64 and is provided at its extremities with circumferential flanges 67. Parallel arms 66 are secured to flanges 67 perpendicular to the axis of tubular member 65. A transverse slot 68 is provided passing thru the mid-section of tubular member 64, and a pin 69, pivotally secured within said member 64, is provided with a diametrical threaded hole 70 in alignment with said slot 68. Axially aligning holes 71 are provided in the ends of arms 66, the axis of said holes being parallel to and in the same plane as the axes of tubular members 64 and 65.

A pin 72 is provided for pivotally securing the elevating assembly to elevating unit housing 29. This pin 72 is assembled through cylindrical bearings 30, holes 71 in arms 66, and tubular member 41. A bolt 73 with a hand nut 74 is assembled thru tubular member 65 and arcuate slots 31 in elevating unit housing 29 for locking the elevating assembly in approximate position. Final adjustment of elevation is accomplished by means of (right and left hand threaded portions) screw 75 having threadably engaging pins 45 and 69 in sleeves 44 and 64 respectively. A knob 76 is provided on screw 75 for adjusting same.

In order to secure carriage 20 in any desired azimuth position and to guide the rotation there-

of, two fixed guides 80 and one adjustable locking guide 81 are provided for assembly in channels 17 by means of removable pins 82 and 83 assembled thru holes 18 and 19 in channels 17 and holes 84 and 85 in the upright portion of guides 80 and 81 respectively. A shoe 86 (Fig. 6) is attached to the underside of the horizontal portion of each guide 80, said shoe 86 slidably engaging bearing strip 27 of carriage 20 and thereby imparting a guiding action to the rotation of the carriage. Locking guide 81 (Fig. 7) differs from fixed guide 80 in that its shoe 87 is vertically adjustable by means of a screw 88 and a fixed pointer 89 is provided thereon for indicating position on azimuth scale 24.

Auxiliary base supports 90 (Figs. 1 and 3) provide additional stability to the mount. Each support consists of a straight leg 91 with a fabricated steel spade-like foot 92 which is secured at the outer end by a pivot pin 93, and a bearing bracket 94 near the middle along the top side, and is pivotally secured to the base 10 by means of pin 83 thru the lower pair of holes 19 in channel 17. Any conventional type of expansion member is mounted between the base and each leg, such as a turnbuckle 95 with tubular bearings 97 and 98 at each end and is secured between bearing bracket 94 and the upper pair of holes 18 in channel 17 by means of pins 93a and 82 respectively. Pins 82 and 83 are readily removable and secured against loss by chains 99 by means of which they are fastened to base 10.

The mortar 100 is of course provided with a conventional breech cap 101 and ball 102. To set up the mount, the base 10 is placed in the desired location and leveled as accurately as possible. Base support legs 91 are secured to the base by insertion of pins 82 and 83 and turnbuckle 95 tightened causing supports 90 to bite into the ground. With the upper pin 82 removed from the channel 17 holding the adjustable guide 81, said guide 81 is swung out on pin 83 and the carriage 20 is placed on base 10 with bearing cup 22 nested in cup 13 in base 10 and bearing strip 27 under shoes 86 of guides 80. Locking guide 81 is now swung into position and secured by upper pin 82 and shoe 87 is tightened against bearing strip 27 by adjusting screw 88. The mortar 100 is then placed in position with ball 102 in bearing cup 22 and split collar 59-60 secured around the mortar barrel.

When the mortar has been set in approximately the desired azimuth position as indicated by pointer 89 on scale 24, screw 88 in locking guide 81 is tightened, thereby locking carriage 20 in position. Final adjustment for azimuth is made by means of knob 56 on the elevating unit 40.

With nut 74 loosened, the mortar 100 is now manually set at the approximate elevation desired by force applied to handle 42 and nut 74 tightened to lock tubular member 65 in fixed position, thereafter screw 75 is turned to accomplish final adjustment for elevation.

When it is desired to remove or replace the auxiliary base supports, turnbuckle 95 is taken up till all pressure is gone from foot 92 and then pins 82 and 83 are removed disengaging said auxiliary base supports which are then removed and pins 82 and 83 replaced securing the corresponding guides in place.

It is therefore apparent from the foregoing description and drawings that this invention provides a mortar mount that can be readily handled in the assembled condition, by a limited number of men, that can be easily and quickly

disassembled into pack-units of reasonable size and weight for personnel transportation and be easily and quickly reassembled and accurately set and adjusted for both azimuth and elevation.

I claim:

1. An adjustable mortar mount comprising a base, a carriage rotatably mounted thereon for movement about a vertical axis, a socket on said carriage for supporting the breech end of a mortar while permitting limited aiming motion of said mortar, means for securing said carriage in any desired rotative position relative to said base, an elevating means for said mortar mounted on said carriage, said elevating means comprising a support unit arranged to engage the barrel of said mortar, means for pivoting said support unit about a horizontal axis, a linkage for converting said pivotal movement of said supporting means to a corresponding elevating or depressing movement of said mortar barrel.

2. In a mortar mount having a base member and a bearing arranged to receive the cap of a mortar therein to thereby support a mortar for pivotal movement about a horizontal axis, the improvement comprising a bracket member, means on the base member for pivotally supporting one end of said bracket member for movement about a horizontal axis displaced from the horizontal axis of the bearing, means for securing said bracket member in any desired pivotal position, a clamp member arranged to rigidly engage the barrel of the mortar, and means for pivotally mounting said clamp member on the other end of said bracket member, said last mentioned means permitting relative linear movement between said clamp member and said bracket member whereby the clamp member may pivot in a vertical plane about the axis of the bearing when the bracket member is pivoted about its said horizontal axis.

3. In a mortar mount having a base member and a spherical bearing on the base member arranged to receive the spherical cap of a mortar therein, the improvement comprising a bracket member, means on the base member for pivotally supporting one end of said bracket member for movement about a horizontal axis, means for securing said bracket member in any desired pivotal position, a clamp member arranged to rigidly engage a mortar, and a linkage interconnecting said clamp member and the other end of said bracket member, said linkage including means for adjusting the azimuthal position of said clamp member relative to said bracket member.

4. In a mortar mount having a base member, the base member having a spherical bearing arranged to receive the spherical cap of a mortar therein, the improvement comprising a bracket member, means on the base member for pivotally supporting one end of said bracket member for movement about a horizontal axis displaced from the axis of said spherical bearing, means for securing said bracket member in any desired pivotal position, a clamp member pivotally secured to said bracket member and arranged to rigidly engage the mortar, and a linkage interconnecting said clamp member and the other end of said bracket member, said linkage including means for adjusting the azimuthal position of said clamp member relative to said bracket member, said linkage having sliding engagement with said bracket member for linear movement relative thereto whereby the clamp member may pivot in a vertical plane about the axis of said

spherical bearing when said bracket member is pivoted about its said horizontal axis.

5. A mortar mount having a base member and a spherical bearing on the base member arranged to receive the spherical cap of a mortar therein, the improvement comprising a bracket member, means on the base member for pivotally supporting one end of said bracket member for movement about a horizontal axis displaced from the axis of said spherical bearing, means for securing said bracket member in any desired pivotal position, a clamp member pivotally secured to said bracket member and arranged to rigidly engage the mortar, a slide member slidably mounted on the other end of said bracket member for linear movement relative thereto, a connecting member slidably secured to said clamp member for movement parallel to the axis of the supported mortar, and means for securing said connecting member to said slide member whereby the clamp member will pivot in a vertical plane about the axis of said spherical bearing when said bracket member is pivoted about its said horizontal axis.

6. The combination defined in claim 5 wherein said means for securing said connecting member to said slide member comprises a screw transversely disposed relative to the path of linear movement of said connecting member and arranged with respect to said slide member and said connecting member whereby rotation of said screw produces an azimuthal displacement of said clamp member relative to said base member.

7. In an adjustable mount for a mortar having a base, a carriage rotatably mounted thereon for movement about a vertical axis, and a spherical bearing mounted on the carriage to receive the spherical cap of a mortar therein, the improvement comprising a bracket member having a pair of spaced longitudinal arms, means for pivotally mounting the bracket member on the carriage for movement about a horizontal axis displaced from the axis of said spherical bearing, each of said bracket arms terminating in a rod-like portion, a sliding yoke having a pair of bushings, each respectively slidably engaging one of said rodlike portions, a clamp member arranged to rigidly engage a mortar, a connecting yoke member slidably secured to said clamp member for linear movement relative thereto and an adjusting screw interconnecting said sliding yoke member and said connecting yoke member, said screw being constructed and arranged with respect to said sliding yoke member and said connecting yoke member whereby rotation of said screw produces an azimuthal displacement of said clamp member relative to the base.

8. An adjustable mount for a mortar, said mount comprising a generally circular base, a plurality of bracket members secured in spaced relationship about the periphery of said base, a plurality of support legs respectively removably secured to said bracket members by pins, a carriage rotatably mounted on said base, means on said carriage for supporting a mortar, said carriage having a circular bearing flange, a plurality of guide members respectively secured to said bracket members by said pins, said guide members engaging said bearing flange to impart a guiding action to the rotation of said carriage, and means for adjusting at least one of said guide members relative to said bearing flange whereby said carriage may be secured in any desired rotative position relative to said base.

9. The combination defined in claim 2, wherein

the means for securing said bracket member in any desired pivotal position about its said horizontal axis comprises a positioning member, means for pivoting said positioning member about said horizontal axis, screw clamp means for securing said positioning member in any desired pivotal position, and an adjusting screw interconnecting said bracket member and said positioning member and arranged with respect thereto whereby adjustment of said adjusting screw produces a pivotal movement of said bracket member about its said horizontal axis relative to said positioning member.
